ROD WEIGHT COMPENSATOR FOR WELL PUMPS

John B. Reilly, Whittier, Calif.

Application October 11, 1952, Serial No. 314,261

3 Claims. (Cl. 103—202)

1
This invention relates to means to counterbalance or compensate for the weight of the string of sucker rods to the lower end of which is connected a pump piston or like reciprocating member.

In wells of relatively shallow depth, the wear on the relatively short reciprocating string of sucker rods that operates the piston of a pump drawing liquid from the well is usually not so great as to cause breakage of the rods. The weight of such a short string is not great enough to abnormally stress the same beyond the ability of the joints in said string, and the rods themselves, to safely absorb such stress. String breakage is, therefore, infrequent. However, as the depth of the well increases, the length and, therefore, the weight of the string of sucker rods increases, resulting in materially increased stresses on said string during reciprocation and more frequent breakage of the string.

In wells 10,000 to 12,000 feet or more deep, the sucker rod string becomes so heavy and, therefore, so greatly stressed, that it has become necessary to reduce the size and, therefore, the capacity of delivery of a pump to enable reduction in the diametral size of the string. Otherwise, the string is prone to breakage.

Recognizing the desirability of retaining the normal delivery capacity of a pump in a deep well, it is an object of this invention to provide the sucker rod string that reciprocates the piston of said pump with means to counterbalance or compensate for the weight of at least a material portion of said string to, thereby, materially reduce breakage of said string due to stresses set up therein during reciprocation. Such means may be single or plural depending on the depth of the well; the greater the depth, the greater the requirement for two or more weight compensating means.

A sucker rod string, as mentioned above, operates in tubing which conducts to the surface of the well the material that is displaced upward by the piston at the lower end of the string. Such tubing, being stationary, is better able to absorb stresses than is the reciprocating string. Therefore, it is another object of the invention to transmit at least a material part of the stresses in the string to the tubing in which it reciprocates.

It is common practice to have an engine at the surface to reciprocate the string. It is a corollary object of the invention to reduce wear on such engine and its bearings by reducing the weight force of the string on said engine.

2
While the differential of weight force remains substantially the same during reciprocation, the engine is relieved of much of the weight of the string by means of the compensator herein contemplated.

The present means also serves as a vibration-dampening agent and has a dash pot action that minimizes build-up of harmonic vibrations.

The invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawing merely shows and the following description merely describes one embodiment of the present invention, which is given by way of illustration or example only.

In the drawing, like reference characters designate similar parts in the several views.

Fig. 1 is a broken elevational view of a well pump shown with two compensators for the weight of the string that operates said pump, the well casing in which the pump is disposed being shown in longitudinal section.

Fig. 2 is an enlarged longitudinal sectional view of one of the compensators shown in Fig. 1. With particular reference to Fig. 1, a conventional casing 5 extends from the surface 6 to the bottom of the well 7. In the usual manner, oil or other liquid fills the well bottom as, for instance, to a level 8. Such level may vary but, in any case, is in the lower portion of the well. In order to remove such liquid and discharge the same above surface 6, as indicated by the arrow 9, a generally conventional pump 10, at the lower end of tubing 11, is lowered into casing 5 and clear of said casing as shown by the annular space 12. Thus, above the liquid level 8, said casing contains an atmosphere in said space that is under relatively low pressure, the same being open at the well surface.

In the usual manner, pump 10 comprises a cylinder 13 provided at its lower end with a standing check valve 14, and with a reciprocating plunger 15 provided with a traveling check-valve 16. It will be clear, without further explanation, that upward movement of the plunger draws liquid from the well past valve 14 into cylinder 13, that downward movement of said plunger upwardly displaces liquid in said cylinder past

valve 16 into the interior 17 of tubing 11, and that repeated reciprocations of the plunger will result in the liquid rising in tubing 11 until the same discharges in the direction of arrow 9. Thus, in conventional pumps, the string of sucker rods 18 that carries plunger 15 and reciprocates the same, moves through the volume of liquid in the interior 17 of casing 11.

The present means 19 for counterbalancing or compensating for a material portion of the weight of sucker rod string 18 is provided in the above-described and generally conventional well pump. While two such means are shown in Fig. 1, only one may be used or, if the well is quite deep, more than two may be used. In Fig. 1, the dimensions 20 may each be in the nature of 5000 or 6000 feet and the dimension 21 may be as great or less, as desired. These dimensions are by way of example because the intent is to provide a means 19 at such distance below the well surface that the same will support a material part of the weight of string 18 to relieve the same of abnormal stresses that may cause breakage. Most deep wells of, for instance, 10,000 to 12,000 feet in depth, may require but one means 19 to provide support that would reduce the stresses in the string to the point where the same is no longer a breakage-causing factor. Still deeper wells may require two or more such means 19 to provide a safe reduction of stresses in the string 18.

With more particular reference to Fig. 2, the means 19 comprises, generally, a rod 22 interposed in the sucker rod string 18 and, therefore, constituting a part of said string, a piston 23 on said rod and of a diametral size to have its lower end 24 materially larger than rod 22 and of substantial area, a cylinder 25 within tubing 11 and in which piston 23 reciprocates as the string 18 reciprocates, said cylinder 25 being clear of tubing 11 to provide an annular space 26 therebetween, an anchor 26^a for the upper end of cylinder 25 and connecting the same to tubing 11, a by-pass 27 around said anchor and communicating the interior 17 of tubing 11 below said anchor with said interior above the anchor, one or more ports 28 through the anchor and tubing and communicating the interior 29 of cylinder 25 above piston 23 with the annular space 12 between casing 5 and tubing 11, and a bearing 30 for rod 22 that also seals interior 29 from interior 17 above the anchor and by-pass.

Rod 22 with piston 23 thereon comprises a unit which can be incorporated in string 18 by the usual box and pin connections conventionally employed to connect sucker rods to form a string.

Cylinder 25 is open at its bottom 31 and is of a length to house piston 23 for the full stroke of string 18 and pump plunger 15.

Anchor 26^a comprises a packing body 32 that fits a packing shoe 33 formed on or provided in tubing 11, and two longitudinally spaced packing rings 34 carried by the body and tightly engaged with the shoe. Conical shoulders 35 on said body and shoe locate said anchor, and the cylinder extending downwardly therefrom, longitudinally in tubing 11.

Ports 28 are located between packing rings 34 so that the same are effectively sealed from the interior 17 of tubing 11 and, therefore, seal said interior from casing space 12 and the upper end 29 of cylinder 25 which said ports connect. By-pass 27 is provided to by-pass around packing

rings 34 and provide communication between interior 17 above and below said packing rings.

Bearing 30 is shown in the form of an elongated stuffing box in which packing 36 seals around rod 22.

Since space 12 is under low or atmospheric pressure, the interior 29 of cylinder 22 above piston 23 is also under such low pressure by reason of communicating ports 28. All other spaces, namely, interior 17 (both above and below the anchor), annular space 26, and by-pass 27, are under the pressure of the liquid being pumped upwardly by pump 10. Since this liquid extends to the surface 6 of the well, the same has a substantial head. Therefore, the latter-mentioned spaces are under high pressure in comparison to the low pressure in spaces 12 and 29.

When the string 18 is moved down, the surface 24 of piston 23 encounters the resistance of the head of liquid in tubing 11. Therefore, the weight of said string above said piston is offset by said resistance in the ratio of the weight of said string and the head of said liquid. Thus, a material part of the string weight is counterbalanced by the liquid head.

When the string is moved up, the piston 23 moves through low pressure in interior 29 while its bottom face 24 is subject to the above-mentioned liquid head. Therefore, the string, above said piston, is counterbalanced, as before, by said head.

Thus, at all times, the weight of the string is, in part, counterbalanced and the stresses therein are materially reduced. Whatever reduction of stress in the string occurs is transmitted to tubing 11. Since said tubing is stationary, the same is better able to absorb the stresses without breakage than is the reciprocating string 18.

It will be realized from the foregoing that the top of piston 23 is sealed off from the liquid pressure and head in tubing 11 and operates in an atmosphere that is vented to the well casing 5. Consequently, whether piston 23 is moving up or down or is at rest, only the under face 24 thereof is subjected to high pressure that hydraulically compensates for part of the string weight.

It will be clear from the foregoing that piston 23, during its downward stroke, acts in the manner of a dash pot on the liquid displaced thereby. Said piston, therefore, serves to dampen any vibrations that may be set up in the long string of sucker rods. Such dampening, by destroying or, at least, greatly minimizing vibration, prevents build-up of harmonic vibrations that are a major cause of metal fatigue.

While I have illustrated and described what I now contemplate to be the best mode of carrying out my invention, the construction is, of course, subject to modification without departing from the spirit and scope of the invention. It is, therefore, not desired to restrict the invention to the particular form of construction illustrated and described, but to cover all modifications that may fall within the scope of the appended claims.

Having thus described the invention, what I claim and desire to be secured by Letters Patent is:

1. In a well having a length of tubing extending longitudinally therein and a pump in the lower end of said tubing to displace material from the bottom of the well upwardly through said tubing, a reciprocative string extending longitudi-

dinarily in said tubing to operate said pump, the improvement that comprises an upwardly-facing conical seat around the interior of said tubing, a tubular device around said string and provided with a downwardly-facing conical portion in engagement with said conical seat and limiting the downward position of said tubular device in said tubing, packing between said device and the tubing below the area of engagement between the conical seat and portion, a bottom-open cylinder extending from the lower end of said device and of an outer diametral size to be inserted from above the conical seat into the tubing therebelow, a stuffing box carried by the tubular device to seal around the string, a piston on the string and operative in said bottom-open cylinder during reciprocative movement of the string, a by-pass in said tubing for the production of the pump around the mentioned packing and the area of contact of the conical seat and part, and a vent communicating the mentioned cylinder above the piston therein to pressure lower than the pressure produced by the pump.

2. The improvements according to claim 1: said packing comprising at least two longitudinally spaced packing rings, and said vent extending laterally through the tubing and the tubular device between said packing rings.

3. In a well having a length of stationary tubing extending longitudinally therein and a pump in the lower end of said tubing to displace material from the bottom of the well upwardly through said tubing, a reciprocative string extending lon-

gitudinally in said tubing to operate said pump, the improvement that comprises a bottom-open cylinder within and spaced from said tubing, said cylinder being carried by the string, interengaging shoulders on the tubing and the cylinder whereby the string is insertable into the tubing from above upon introduction of the string into the tubing and removable with the string during upward extraction of the latter while the tubing remains stationary, said interengaging shoulders on the tubing and the cylinder locating the latter in an intermediate part of the tubing, a piston reciprocative with the string and operative in the cylinder, a seal between the upper end of the cylinder and the string, a vent communicating the mentioned cylinder above the piston therein to pressure lower than the pressure produced by the pump, and a by-pass in said tubing for the production of said pump around the mentioned interengaging shoulders, the head of the production material in said tubing being effective through said by-pass and the space between said tubing and cylinder to produce on the bottom face of said piston an upward force that, in part, counterbalances the weight of the string.
